UNITED STATES PATENT OFFICE.

AUGUST BLESER, OF LYNBROOK, NEW YORK.

GAME APPARATUS.

Application filed November 1, 1921, Serial No. 512,016. Renewed December 11, 1924.

To all whom it may concern:

Be it known that I, AUGUST BLESER, a citizen of the United States, and a resident of Lynbrook, in the county of Nassau and 5 State of New York, have invented a new and Improved Game Apparatus, of which the following is a full, clear, and exact description.

This invention has relation to games or 10 toys and refers more particularly to an apparatus by means of which several games may be played.

The invention contemplates a highly 15 amusing and attractive game apparatus for affording amusement to both young and old, and in which the elements of skill and luck enter in proper proportions to make the games played thereby of interest.

As a further object the invention aims to 20 provide a game apparatus which is extremely simple in its construction, inexpensive to manufacture and which may be folded into a compact article when not in use for storage or shipment.

25 With the above recited and other objects in view, the invention resides in the novel construction set forth in the following specification, particularly pointed out in the appended claims and illustrated in the accompanying drawings, it being understood 30 that the right is reserved to embodiments other than those actually illustrated herein to the full extent indicated by the general meaning of the terms in which the claims 35 are expressed and by variations in the phraseology of the same.

In the drawings—

Fig. 1 is a plan view of the apparatus set up with the cover or lid in section.

40 Fig. 2 is a sectional elevation thereof taken approximately on the line 2—2 of Fig. 1.

Fig. 3 is a longitudinal sectional view taken approximately on the line 3—3 of 45 Fig. 2 and illustrating one of the uses of the apparatus.

Fig. 4 is a similar fragmentary view illustrating another use of the apparatus.

Referring to the drawings by characters 50 of reference the apparatus consists of a box comprising a body 10 and a cover or lid 11 adapted to normally fit over the body which is designed to contain the remaining elements or pieces of the apparatus when 55 not in use. The bottom wall 12 of the body is inscribed adjacent one end, (hereafter

termed the rear end) on its upper surface with a triangular field 13 provided with spots 14 following the arrangement of the spots on a bowling alley for the placement 60 of ten pins. Intermediate of the upper surface of the bottom wall, a hinged partition 15 is secured having a central opening 16 therein, said partition being designed, when not in use, to be folded to an out-of-the-way 65 position to lie parallel with the bottom wall 12, as illustrated in Figure 3. At the opposite or front end, the bottom wall is provided with a centrally disposed circular opening or aperture 17 in front of which a 70 spot 18 is inscribed. An angularly disposed slit 19 is provided in each side wall 20 of the body of the box, the same extending from the upper edge of the side wall downwardly and forwardly and terminating at a 75 point slightly above the juncture of the side walls with the bottom. The upper or intermediate notch 21 communicates with each slit 19 and a lower notch 22 communicates with each slot 19 at its lower terminal. The 80 cover or lid 11 has inscribed on the inner surface thereof a target 23 which is disposed adjacent one extremity thereof. The playing pieces or elements consist of a ball 24 and ten pins 25 equal in number to the 85 number of spots 14 on the triangular field 19; a dart 26 and an elastic or rubber band 27 which is passed over the body of the box with one of the leads respectively inserted in the slits 19 in the opposite walls 20. 90

In practice the user may either employ the apparatus as an archery game for catapulting the dart by means of the elastic band 27 to cause the same to be projected into the target or as a bowling game in which instance the ball and pins are used. When employed as an archery game, the cover or lid 11 is removed and placed over the rear end of the box body as illustrated in the drawings to dispose the target 23 in a vertical position. The dart 26 is then inserted in the bottom 12 of the box body substantially at a point indicated by the spot 18, said dart being preferably disposed at an angle. In this instance the upper lead of the elastic 100 band is shifted into the upper or intermediate notches 21 and the user by manipulating and expanding the band and then releasing the same, employs said band as a catapult for projecting the dart from the spot to the 110 target, the lid serving as a fender to prevent wild shots from injuring persons or

articles of furniture in rear of the game apparatus. It is, of course, obvious that any method or rules for playing the archery game may be promulgated according to the manufacturers and players.

When the apparatus is employed as a bowling game, the hinged partition 15 is swung upwardly to occupy a vertical position or a position at a right angle to the bottom wall 12 of the box body to serve as a baffle against wild shots. The ten pins 25 are then set up on the spots 14 in the triangular field 12 and the ball 24 is arranged or positioned in the opening 17. The upper lead of the elastic band 27 is then shifted from the notches 21 to the lowermost notches 22 and the operator by stretching the band under tension toward the front wall of the box releases the same to project the ball 24 through the opening 16 in the partition 15 for the purpose of knocking down the ten pins 25.

It will thus be seen that a simple, inexpensive, highly amusing and attractive game apparatus is provided which may be employed for the playing of various games and which when not in use may be folded to occupy a minimum amount of space for storage or shipment.

30 I claim:

1. In a game apparatus, the combination with a ball game including a ball and ten pins, and an archery game including a target and dart, of a box including a body and cover constituting a container and support

for the bowling and archery game elements, and a common catapulting element for projecting either the ball against the pins or the dart against the target consisting of an elastic band, angularly disposed slotted portions in the opposite side walls of the box having vertically spaced notches communicating therewith for the reception of the upper lead of the elastic band to dispose the same respectively in separate vertical planes to cooperate with the ball or dart.

2. A game apparatus including a box body having spots inscribed on the upper surface of its bottom wall, a plurality of ten pins adapted to be positioned on said spots, a baffle wall having a central opening therethrough and hingedly secured to the upper surface of the bottom wall intermediate its ends, a removable lid having a target inscribed on the inner surface thereof adapted when the lid is removed and placed over the rear end of the box body to dispose the target vertically and at a right angle to said box body, a ball, a dart, and a common catapulting element arranged adjacent the front end of the box body for respectively projecting the ball through the opening in the baffle wall to knock down the ten pins or the dart onto the target, said box body having means with which the catapulting element is adapted to coact for effecting vertical adjustments thereof whereby to arrange the same in a plane to coact with either the dart or ball.

AUGUST BLESER.
